METHOD FOR CLEANING DIFFUSER TUBES

Miles A. Lamb, Chicago, and Joseph J. Klein,
Glencoe, Ill., assignors to Chicago Pump Com-
pany, a corporation of Delaware

Application December 29, 1949, Serial No. 135,782

9 Claims. (Cl. 134—29)

1

This invention relates to a method for cleaning diffuser tubes used for the aeration of liquids or for the dispersion of gases or vapors therein. More specifically, the invention relates to the cleaning of diffuser tubes in which the air or gas is supplied under pressure and passes through pores in the tube into the liquid. The invention has particular adaptability to the cleaning of the type of tube in which the pores are formed by tight windings of non-circular twisted cord wound upon a tubular core, such as is disclosed in the co-pending application of Carl H. Nordell, which issued as Patent No. 2,555,201 on May 29, 1951.

The cleaning of diffuser tubes presents a substantial problem in the operation of plants employing such tubes, for example plants engaged in the activated sludge process of treating sewage. In the course of time, such diffuser tubes become badly contaminated with sediment and grease, both due to deposits of solid matter from the liquids in which the tubes are placed, and to impurities such as dust and grease in the input air which is diffused through the tube. When the minute pores of the tube are thus blocked, the pressure drop across the porous medium, and thus the volume of flow for any given input air pressure, are seriously reduced. Thus with the passage of time the efficiency of the aeration process in which the tube is employed is greatly impaired. It thus becomes necessary to periodically clean the diffuser tubes to restore the pores to their original condition.

The methods and apparatus for cleaning such diffuser tubes heretofore in common use have required the expenditure of extensive time by trained personnel for adequate cleaning. In addition to the time required, many of the methods heretofore employed required the use of strong acid or alkaline cleaning solutions, thus requiring special handling and protection of personnel in the cleaning of the tubes, and further adding to the cost of the cleaning operation.

The present invention provides a method whereby the tubes may be cleaned rapidly and inexpensively. By the method of the present invention, the amount of labor required in the cleaning of the tubes is made small. Furthermore, the present invention completely eliminates the use of strong and potentially harmful cleaning solutions in the cleaning of such diffuser tubes. Additionally, the apparatus for cleaning such tubes provided in accordance with the invention is extremely simple and inexpensive both to manufacture and to operate.

2

For a full understanding of the invention, reference is made to the illustrative embodiment shown in the drawings, in which:

5 Fig. 1 is an elevational view, partly in section, of a diffuser tube, showing the manner of attachment to an air inlet header;

Fig. 2 is a transverse sectional view of the diffuser tube of Fig. 1, taken along the line 2—2 in the direction indicated by arrows;

10 Fig. 3 is an enlarged fragmentary sectional view taken along the line 3—3 of Fig. 2 in the direction indicated by arrows;

15 Fig. 4 is an enlarged fragmentary view, partially in elevation and partially in section, taken along the line 4—4 of Fig. 3 in the direction indicated by arrows;

Fig. 5 is a plan view of a cleaning apparatus embodying the present invention;

20 Fig. 6 is a vertical sectional view of the cleaning apparatus of Fig. 5, taken substantially along the line 6—6 of Fig. 5 in the direction indicated by arrows, and illustrating the manner of performing a portion of the cleaning operation of the invention;

25 Fig. 7 is an enlarged sectional view of a portion of the cleaning apparatus taken along the line 7—7 of Fig. 6 in the direction indicated by arrows;

30 Fig. 8 is a vertical sectional view taken along the line 8—8 of Fig. 7, and illustrating the manner of disposition in the apparatus of a diffuser tube subjected to a step in the cleaning process of the invention.

35 One type of diffuser tube now in common use is the diffuser tube of the general type described in Patent No. 2,555,201 of May 29, 1951. This type of diffuser tube has achieved substantial success, particularly in the activated sludge process for treating sewage, because of its simplicity and in-

40 expensiveness and its efficiency in diffusion of air. However, the cleaning of diffuser tubes of this type has proven to be a vexing problem. Although such diffuser tubes are not in themselves any part of the present invention, an example

45 of such a diffuser tube is illustrated in Figs. 1 through 4 of the drawing and described below in order to facilitate understanding of the difficulties encountered in cleaning such tubes, and to further facilitate understanding of the manner in which the cleaning problem of this tube and other diffuser tubes, such as those made from ceramic material or carbon, may be solved by the process and apparatus of the present invention.

Referring first to Fig. 1, the reference numeral 18 indicates an air main having an opening 12 into which the open end of a diffuser tube, generally indicated by the numeral 14, is threaded. The diffuser tube 14 comprises a hollow core 16 of steel or other suitable material, depending upon the characteristics of the materials with which it is designed to come in contact, a winding 18 of cord which covers virtually the entire core and a pair of end caps 20 and 22, which may be formed of the same material as the core. The core 16 is an open ended cylindrical tube to the ends of which caps 20 and 22 are secured in any suitable manner, preferably by welding. The ends of the winding cord 18 are secured by the knot 24 and the bolt 26. The inner end cap 22 has an exteriorly threaded neck 28 which is screwed into the threaded opening 12 in the air header 10. The outer end cap 20 has secured thereto, as by welding, an eye 30.

As seen more clearly in Fig. 2, the core 16 is corrugated or fluted to provide alternate ridges 32 and valleys 34 extending longitudinally of the core. A plurality of orifices or openings 36 is provided in each of the valleys 34 for the passage of air or gas from the inside of the core 16 into the long small chambers 38 formed on the outer surface of the tube 16 by the alternating ridges and valleys 32 and 34, and by the windings 18, which bridge the valleys 34.

The cord of the windings 18 may be formed of two or more strands of a suitable material such as a vinyl resin of the type commercially known as "Saran," which is formed from a copolymer of vinyl chloride and vinylidene chloride. In the particular diffuser tube structure illustrated in Fig. 3, the winding cord 18 consists of three strands of the above-mentioned plastic material. These strands are tightly twisted in rope-like form, as illustrated in Fig. 4, and are wound sufficiently tightly so that adjacent turns of the winding are slightly compressed. In this manner there are created between adjacent turns 42a and 42b of the winding 18 a large number of very fine pores or passageways 44, forming a more or less uniform pattern through the interface between the adjacent turns.

As stated above, the diffuser tube structure illustrated in Figs. 1 through 4 of the drawing, and described above, constitutes in itself no part of the present invention, but is presented to aid in the understanding of the invention.

As further stated above, there arises in the operation of plants employing such diffuser tubes a continuous problem of maintenance due to the necessity of periodically cleaning the tubes in order to prevent the occurrence of excessive pressure drops in the tubes, which would obviously interfere with the proper operation of the aeration process. The method commonly employed for such cleaning is the application of high pressures to the tubes from the inside. This application of pressure is commonly preceded by pre-treatment of the tube with strong agents such as acid or alkali cleaning solutions, the tube being bathed in the solution. The soil is then flushed from the tube by applying a fluid pressure, either of a gas such as air or a liquid such as water, or a mixture thereof, to the interior of the tube.

It is found that such methods are not only highly laborious, but are additionally relatively ineffective in cleaning diffuser tubes of the type illustrated in Figs. 1 to 4 of the drawing and described above. Although the exact reasons for

the failure of such prior art methods to produce satisfactory cleaning of the tubes are not precisely known, it is believed that the difficulty is due to the fact that any cleaning agent which is sufficiently strong to dissolve the soil or to disperse the soil into sufficiently fine particles to pass through the extremely fine pores 44, is likewise sufficiently strong to carbonize and fix organic materials lodged in and on the diffuser tube. Thus it is believed that the bathing of the tube in even the strong solutions heretofore employed leaves much of the soil in the form of finely dispersed particles in the elongated chambers 38. As the liquid cleaning agent is poured off upon removal of the tube from the cleaning solution, much of this soil is again deposited upon the interior surfaces of the windings 18 and the surface of the valleys or flutes 34. When fluid pressure is subsequently applied to the diffuser tube, either by the application of high air pressure, or by the insertion of water under pressure, in an attempt to "blow" the particles of soil out through the pores 44, the soil is again deposited in the pores and formed into small masses which partially block the porous wrapping. It has been found that a considerable number of cycles of this type of cleaning operation are required for complete cleaning of the tube and restoration of the flow resistance of the pores 44 to their original condition.

Generally, the method of the present invention resides in the discovery that by the application of a liquid, such as water, having a high velocity to the exterior surface of the tube, the liquid may be forced through the pores 44 into the chambers 38 and thus flush out the chambers 38 through the apertures 36. The latter apertures 36 are much larger than the pores 44, so that the soil particles trapped in the chambers 38 do not tend to accumulate at these apertures 36 but freely flow with the liquid into the interior of the core 16. This discovery has enabled the present inventors to devise a method and apparatus for cleaning of diffuser tubes such as those above described which is far more simple and inexpensive than the methods and apparatus heretofore employed.

By applicants' method of cleaning diffuser tubes, the tubes are first cleaned in a simple fashion on the exterior. In most cases, this may be done by ordinary flushing away of exterior soil with a common hose. The diffuser tube is then soaked in a detergent composition containing a surface-active agent for the purpose of loosening the soil from the inner surfaces of the windings 18 and the passageways or pores 44. This soaking is preferably continued for about 10 to 15 hours, but a somewhat shorter time may be employed if the tube is used under conditions where the soiling is extremely slight.

Any well-known type of detergent composition is suitable for use as a bath in loosening the soil which is present in the flutes and the pores. A cationic, anionic or non-ionic surface-active agent may be employed as the sole active constituent of a water solution, but improved results are achieved by the addition of a detergent assistant. In cases where the soil adhering to the windings and the core is relatively easily removed, a solution of a detergent assistant may itself have sufficient detergent action to be satisfactory for employment as the detergent composition.

The preferred detergent compositions include a surface-active agent which is non-sudsing or

has only low sudsing properties, preferably a non-ionic detergent such as that formed by reacting tall oil fatty acids with ethylene oxide. One such detergent is commercially known as MXP, sold by Monsanto Chemical Co. Other suitable surface-active agents are, for example: a sodium alkyl aryl sulfonate, such as is sold by Allied Chemical & Dye Corp. under the name Naccolene F. or Naccolene E; a fatty alcohol sulfate, such as is sold by E. I. du Pont de Nemours Co. under the name Duponol DLS; the dioctyl ester of sodium sulfosuccinic acid, such as is sold by American Cyanamid & Chemical Corp. under the name Aerosol OT; or a mixed fatty acid (C₁₀-C₁₆) alkylolamine condensate such as is sold by Ninol Laboratories under the name Ninol 400. It will be understood that this listing constitutes only a small fraction of the surface-active agents which may be employed in the detergent composition, any of the surface-active agents well known for analogous uses giving reasonably satisfactory results.

The detergent or detergent assistant which may be used in the detergent composition may be, for example: anhydrous or hydrated sodium metasilicate, such as that sold, respectively, as Drymet and Escomet by Cowles Detergent Co.; sodium hexametaphosphate, such as that sold as Calgon by Calgon, Inc.; tetrasodium pyrophosphate, such as sold by Monsanto Chemical Co. under the name Phosphatex; trisodium phosphate; sodium triphosphate; sodium carbonate; sodium metaphosphate, and the like.

The preferred detergent composition for the practice of the method of the invention consists of a water solution of 2% MXP (a product of reaction of tall oil fatty acids with ethylene oxide, mentioned above) and 2% sodium metasilicate.

Following the detergent bath, all portions of the exterior surface of the diffuser tube are then sprayed with water having a velocity of at least 40 feet per second, and preferably of a velocity of greater than 80 feet per second. It is important to note that this spraying operation (involving the impingement of a multiplicity of water jets on the tube) is preferably carried out with the open neck 12 suspended downwardly. This is desirable in order that the water in the elongated chambers 38 will flow freely out of the tube, thus completely and rapidly flushing out through the openings 36 the dirt particles loosened by the bath in the detergent composition. It is found that by this method, the tubes may be cleaned with as little as 30 to 60 seconds of application of the water spray. Such a short application of water jets has been found to restore even the most badly soiled of diffuser tubes employed in the activated sludge sewage process to their original pressure drop conditions after the preliminary washing of the exterior, and bathing of the tubes in a suitable detergent composition. In the case of badly soiled tubes, the preliminary step of cleaning the exterior of the tube prior to the bath in the detergent composition is performed with high velocity jets similar to those employed in the final step, rather than with an ordinary hose, which is, however, suitable where the tube is only mildly soiled.

There is illustrated in Figs. 5 through 8 one manner in which the high velocity spraying of the present invention may be performed, and a simple, inexpensive and efficient apparatus for this purpose. As shown in these figures, the high velocity spraying process is carried out in a cylind-

rical tank 50 having at the bottom thereof a drain 52. A spray jet assembly, generally designated by the numeral 54, is supported in the interior of the tank 50 near the top thereof by a support bracket 56 which rests on the edge of the tank 50, and on the diametrically opposite side by an inlet pipe 58 which is supported by and extends out through an aperture 60 in the wall of the tank 50.

The inner end of the bracket 56 is secured as by a weld 62 to the outer surface of a short tubular member 64. The diametrically opposed portion of the tube 64 is provided with a coupling 66 receiving the input pipe 58. Coaxial with the tube 64 is a second short tubular member 68 of smaller diameter. Secured to the upper edges of the tubes 64 and 68, as by welding, is an annular plate 70 having an outer diameter equal to the diameter of the tube 64 and an inner diameter somewhat smaller than the diameter of the tube 68.

Secured to the bottom ends of the tube members 64 and 68 is an annular plate 72, thus forming an annular water ring 80. The plate 72 has bored therein a circular series of passages 74 extended generally inwardly and downwardly from the upper face of the plate to the inner face thereof, the inner face 76 being bevelled so that the orifices or bores 74 are substantially perpendicular to the inner face 76. The bores 74 are inclined downwardly to form an angle of approximately 60 degrees with the axis of the tubes 64 and 68.

The inner edge 78 of the upper annular plate 70 serves to maintain the centered position of the diffuser tube 14 as it is passed through the assembly 54, as shown in Fig. 8. The downward inclination of the bores 74 has been found desirable in order to avoid the possibility of compacting soil remaining after the preliminary cleaning, into the outer portions of the pores 44. By spraying at an angle with respect to the axis of the tube it is assured that soil remaining on the outer surface will be washed off, rather than forced into the pores 44. However, the angle at which the jets intercept the axis of the tube must not be less than 45 degrees, since lesser angles of incidence result in failure to properly flush the interior of a diffuser tube. Therefore, the angle at which the jet strikes the diffuser tubes should be between 45 degrees and 90 degrees and is preferably 60 degrees, as in the illustrated embodiment. The bevelling of the inner face 76 serves to maintain the jets at the proper angle without the dispersion which has been found to occur in the absence of such bevelling.

The number of jets or orifices 74 is sufficient to secure complete coverage of the surface of a diffuser tube 14 inserted in the central aperture in the upper plate 70. Preferably, the number of equally spaced jets or apertures 74 corresponds exactly to the number of flutes or chambers 38 on the surface of the tube core 16.

In a particular embodiment of the apparatus illustrated in Figs. 5 through 8, the jets 74 were approximately $\frac{3}{2}$ inch in diameter; the water pressure maintained at the inlet pipe 58 was between 40 and 60 pounds per square inch; and the velocity of the jets of water incident upon the windings 16 of the tube 14 was approximately 80 feet per second.

In a typical practice of the method of the invention with the apparatus shown in Figs. 5 through 8 in an activated sludge processing plant, the tubes are sprayed down with an ordi-

nary hose as the first step of the operation, the tubes which are exceedingly soiled being instead passed through the jet apparatus illustrated. Thereafter the tubes are soaked overnight in a solution of 2% MXP referred to above) and 2% sodium metasilicate in water. The tubes are then lowered through the assembly 54 and pulled back up, in a time of approximately 30 to 60 seconds, a cord (not shown) tied to eye 39 being used to facilitate this operation. It is then found that all of the tubes, irrespective of the condition of soil existing before the cleaning process, have been restored to their original pressure loss which was, with one construction of diffuser tube in accordance with Figs. 1 to 15 4, about 8½ inches of water with an air flow rate of 6 cubic feet per minute.

There has been described above the general principles and practices of the invention in conjunction with a particular embodiment of the invention in order to aid in the understanding thereof. It will, of course, be understood that the particular embodiment illustrated is not in itself definitive of the scope of the invention. Therefore, the invention is not to be restricted to the exact structure of the illustrative embodiment described above. Nor is the invention to be limited to the precise steps of the method described above, since obvious variations in these steps will readily suggest themselves to skilled workers in the art.

We claim:

1. A method of cleaning a diffuser tube comprising a hollow foraminated elongated core open at least at one end and having longitudinal outer flutes and a tight winding of non-circular twisted cord on said core forming reticulated pores, said method comprising the steps of progressively moving the tube relative to a plurality of water jets having a velocity of at least 40 feet per second, spraying the exterior surface of the tube with said water jets at an angle of approximately 60 degrees with respect to the axis of the tube in the direction of relative motion of the tube, to clean the outer surface of the tube, soaking the tube in a detergent to loosen soil in the flutes and pores, and again spraying the exterior surface of the tube in the manner aforesaid with the tube vertically disposed and said open end directed downwardly, to flush the soil so loosened through the foramina of the core.

2. A method of cleaning a diffuser tube comprising a hollow foraminated elongated core open at least at one end and having longitudinal outer flutes and a tight winding of non-circular twisted cord on said core forming reticulated pores, said method comprising the steps of progressively moving the tube relative to a plurality of water jets having a velocity of at least 40 feet per second, spraying the exterior surface of the tube with said water jets at an angle of less than 90 degrees and greater than 45 degrees with respect to the axis of the tube in the direction of relative motion of the tube, to clean the outer surface of the windings, soaking the tube in a detergent composition to loosen soil in the flutes and again spraying the exterior surface of the tube in a manner aforesaid with the tube vertically disposed and said open end directed downwardly, to flush the soil so loosened through the foramina of the core.

3. A method of cleaning a diffuser tube comprising a hollow foraminated elongated core having surface recesses and a tight winding of non-circular twisted cord on said core forming

reticulated pores, said method comprising the steps of soaking the tube in a detergent composition to loosen soil in the recesses and pores, progressively moving the tube relative to a plurality of liquid jets having a velocity of at least 40 feet per second, and spraying the exterior surface of the tube with said liquid jets at an angle of less than 90 degrees and greater than 45 degrees with respect to the axis of the tube in the direction of relative motion of the tube, to flush the soil so loosened through the foramina of the core.

4. A method of cleaning a diffuser tube comprising a hollow foraminated core having surface recesses and a porous wrapping on said core, said method comprising the steps of soaking the tube in a detergent composition to loosen soil in the recesses and pores, progressively moving the tube relative to a plurality of liquid jets having a velocity of at least 40 feet per second, and spraying the exterior surface of the tube with said liquid jets in the direction of relative motion of the tube, to flush the soil so loosened through the foramina of the core.

5. A method of cleaning a foraminated diffuser element through which an aeriform body may be forced under pressure and diffused in the surrounding medium, said method comprising the steps of soaking the diffuser element in a detergent composition to loosen soil in the foramina of the diffuser element, progressively moving the diffuser element relative to a plurality of liquid jets having a velocity of at least 40 feet per second, and spraying said diffuser element with said liquid jets in the direction of relative motion of the diffuser element.

6. A method of cleaning a foraminated diffuser element through which an aeriform body may be forced under pressure and diffused in the surrounding medium, said method comprising the steps of progressively moving the diffuser element relative to a plurality of liquid jets having a velocity of at least 40 feet per second, and spraying said diffuser element with said liquid jets in the direction of relative motion of the diffuser element.

7. The method of cleaning a foraminated diffuser element through which an aeriform body may be forced under pressure and diffused into the surrounding medium, said method comprising the steps of progressively moving the element relative to a plurality of liquid jets having a velocity of at least 40 feet per second, spraying the exterior surface of the element with said liquid jets at an angle of approximately 60 degrees with respect to the axis of the element in the direction of relative motion of the element, to clean the outer surface of the element, soaking the element in a detergent to loosen soil in the foramina, and again spraying the exterior surface of the element in the manner aforesaid to flush the soil so loosened through the foramina of the element.

8. The method of cleaning a foraminated diffuser element through which an aeriform body may be forced under pressure and diffused into the surrounding medium, said method comprising the steps of progressively moving the element relative to a plurality of liquid jets having a velocity of at least 40 feet per second, spraying the exterior surface of the element with said liquid jets at an angle of less than 90 degrees and greater than 45 degrees with respect to the axis of the element in the direction of relative motion of the element, to clean the outer surface of the element, soaking the element in a detergent com-

position to loosen soil in the foramina, and again spraying the exterior surface of the element in the manner aforesaid to flush the soil so loosened through the foramina of the element.

9. The method of cleaning a foraminated diffuser element through which an aeriform body may be forced under pressure and diffused into the surrounding medium, said method comprising the steps of soaking the element in a detergent composition to loosen soil in the foramina, progressively moving the element relative to a plurality of liquid jets having a velocity of at least 40 feet per second, and spraying the exterior surface of the element with said liquid jets at an angle of less than 90 degrees and greater than 45 degrees with respect to the axis of the element in the direction of relative motion of the element to flush the soil so loosened through the foramina of the element.
